UNITED STATES PATENT OFFICE

112,765

DESIGN FOR A CASING ELEMENT FOR A SLICING MACHINE

Arthur H. Ahrndt, La Porte, Ind., assignor to
U. S. Slicing Machine Company, La Porte,
Ind., a corporation of Indiana

Application April 29, 1938, Serial No. 76,842

Term of patent 14 years

To all whom it may concern:

Be it known that I, Arthur H. Ahrndt, a citizen of the United States, residing at La Porte, La Porte County, Indiana, have invented a new, original, and ornamental Design for a Casing Element for a Slicing Machine, of which the following is a specification, reference being had to the accompanying drawing, forming part thereof.

Fig. 1 is a perspective view of a casing element

for a slicing machine, showing my new design; and

Fig. 2 is a perspective view thereof, showing the opposite side.

I claim:

The ornamental design for a casing element for a slicing machine, as shown.

ARTHUR H. AHRNDT.
